UNITED STATES PATENT OFFICE

2,535,758

PREHEATING SYSTEM FOR INTERNAL COMBUSTION ENGINES

Otto R. Schoenrock, Oak Park, Ill., assignor to
 J. I. Case Company, Racine, Wis., a corporation
 of Wisconsin

Application May 15, 1948, Serial No. 27,295

6 Claims. (Cl. 123—142.5)

1

This invention relates to preheating systems for internal combustion engines and more particularly to a preheating system which has for its source of heat a small air heating unit.

Various preheating methods have been proposed but such methods have been either too costly to produce or ineffective in their operation at extremely low temperatures. For instance, the method of inserting electric heating coils in the air intake manifold is too expensive as well as bulky in construction because of the very large storage batteries required to supply the needed electric current. Also, the glow plug method has not proven too effective at extremely low temperatures, because it is of a one-shot type heater, and does not produce enough lasting heat. Thus it is the object of this invention to provide an improved preheating system which is inexpensive to produce, compact in construction, and effective in its operation regardless of the severity of low temperatures.

It is a further object of this invention to provide apparatus which will allow the heated air from the air heating unit to be directed to a greater number of parts of the engine and thereby reduce the starting torque which, in turn, will reduce the side battery and starter required for operation of the engine.

Further and additional objects will appear from the description, accompanying drawings and appended claims.

In carrying out this invention, in one form, the source of heat is derived from a small conventional type heater, which has a gas burner and fan in combination with an electric flame igniting device. The heated air from said heater is distributed to the various parts of the engine such as the oil pan, exposed fuel lines, and air intake manifold, by means of a duct and valve arrangement. Controlling means is provided enabling the heated air to be directed to these various parts of the engine either independently, consecutively, or simultaneously depending upon the condition encountered when starting.

For more complete understanding of this invention, reference should now be made to the drawings, wherein:

Figure 1 is a diagrammatic elevational view of the preheating system and an internal combustion engine showing portions of the distributing ducts of the preheating system cut away to expose the valves of said ducts;

Fig. 2 is a diagrammatic elevational view showing the opposite side of the preheating system and internal combustion engine from that shown in Fig. 1;

2

Fig. 3 is a perspective diagrammatic view of the preheating system;

Fig. 4 is a fragmentary front view of the engine showing the duct housing for preheating the exposed fuel lines;

Fig. 5 is a fragmentary sectional view of the duct housing for preheating the oil pan as taken along line 5—5 as shown in Fig. 2.

Referring now to the drawings, the principal embodiments of this invention are an air-heating unit 10, a duct arrangement 12 working in conjunction with said heater 10, and control valves 14 for directing the flow of heated air from said heater 10 to various parts of the internal combustion engine 16. The air heater 10 is of a small, conventional type with a high heat output, preferably that of a hermetic combustion type which has a gas burner and fan in conjunction with an electric flame-igniting device.

The voltage demand for effective operation of heater 10 is considerably less than that required in the electric coil type preheating, thus enabling smaller storage batteries to be used and thereby making the system more compact and lightweight in construction and inexpensive to operate.

The duct arrangement 12, which comprises a plurality of flexible duct branches 18, 20 and 22, distributes the heated air forced from the heater unit 10 to various parts of the engine 16, namely, the oil pan 24, the exposed fuel lines 26, and the air intake manifold 28.

Enclosed within each of the duct branches 18, 20 and 22 is provided a valve 30, 32 and 34 which controls the amount of heated air forced through said ducts.

Control valve 30 within duct branch 18 is of a butterfly type, as shown in Fig. 1, and regulates the preheating of the oil pan 24.

To the end of the duct branch 18 is attached a housing 36 which is shaped to enclose a portion of the oil pan 24 of engine 16, thereby more effectively distributing and directing the heated air around the oil pan. Said housing 36 is fastened to the engine block 16 by bolts or any other suitable means. Means for exhausting the heated air about the oil pan 24 is provided by having the end 38 of the housing 36 open.

Control valve 32 within duct branch 20 is also of a butterfly type and controls the flow of air from the air-heater unit 10 to the exposed fuel lines 26. To the end of said duct branch 20 is attached a duct housing 40 which is shaped to jacket the exposed fuel lines 26 and thereby confine and direct the heated air more effectively to said fuel lines 26. Said housing 40 is attached to the engine block 16 by means of brackets 41,

The outlet for said heated air is at the forward open end 42 of said housing 40.

Control valve 34 in said duct branch 22 controls the amount of heated air from the heater 10 that may pass to the air intake manifold 28. Said control valve 34 is of a gate type and after the engine 16 has been sufficiently preheated and in operation, the gate valve 34 may be moved to a vertical position, as shown in Fig. 1, and thereby cut off the heated air from the heater 10. The air supply for the intake manifold 28 then comes directly from the intake port 44 through duct branches 46 and 22 and by-passes the heater 10 as shown in Fig. 1. Thus control valves 30, 32 and 34 may be adjusted by the operator to direct the flow of heated air from said air heater 10 to the several parts mentioned above, either independently, consecutively, or simultaneously depending on the climatic conditions encountered.

Thus it will be seen from this description that a small, compact, inexpensive and efficient preheating system has been devised which will effectively preheat the engine regardless of the severity of the low temperatures within a short time after being put in operation. While a particular embodiment of this invention is shown above, it will be understood, of course, that the invention is not to be limited thereto since many modifications may be made and it is contemplated, therefore, by the claims to cover any such modifications as may fall within the true spirit and scope of this invention.

Having thus described my invention, what I claim and desire to secure by Letters Patent is:

1. In a preheating system for an internal combustion engine having a plurality of fluid spaces to be heated, the combination of an air-heating unit, means for forcing the heated air from said unit, and means for distributing the heated air forced from said unit to effect heating of said spaces, said means comprising a plurality of valves, a controlling means for operating said valves, and directional ducts to further distribute the air forced from said unit to said fluid spaces.

2. In a preheating system for an internal combustion engine having exposed fuel lines to be heated, the combination of an air-heating unit, and means for distributing the heated air forced from said unit to effect heating of the exposed fuel lines comprising a directional duct housing to enclose said fuel lines, and means for forcing the heated air from said unit to said duct housing.

3. In a preheating system for an internal combustion engine having a plurality of fluid spaces to be heated, the combination of an air-heating unit, means for distributing the heated air forced from said unit to effect heating of the exposed fuel lines and oil pan of said engine, said means comprising directional duct housings shaped to enclose said fuel lines and oil pan, a plurality of valves, and a controlling means for operating said valves, said means allowing both said fluid spaces

to be heated independently, consecutively, or simultaneously, and means for forcing the heated air from said unit to said housings.

4. In a preheating system for an internal combustion engine having a plurality of fluid spaces to be heated, the combination of an air-heating unit, means for distributing the heated air forced from said unit to effect heating of the exposed fuel lines and the air entering the intake manifold of said engine, said means comprising a directional duct housing shaped to enclose said fuel lines, and a directional duct connected to the intake port of said manifold, a plurality of valves, and controlling means for operating said valves, said means enabling both fluid spaces to be heated independently, consecutively, or simultaneously, and means for forcing the heated air from said unit to said duct and duct housing.

5. In a preheating system for an internal combustion engine having a plurality of fluid spaces to be heated, the combination of an air-heating unit, means for distributing the heated air forced from said unit to effect heating of the oil pan and the air entering the intake manifold of said engine, said means comprising a directional duct housing shaped to enclose said oil pan, and a directional duct connected to the intake port of the said manifold, a plurality of valves, and controlling means for operating said valves, said means enabling both fluid spaces to be heated independently, consecutively, or simultaneously, and means for forcing the heated air from said unit to said duct and duct housing.

6. In a preheating system for an internal combustion engine having a plurality of fluid spaces to be heated, the combination of an air-heating unit, means for distributing the heated air forced from said unit to effect heating of the exposed fuel lines, oil pan, and the air entering the intake manifold of said engine comprising directional duct housings shaped to enclose said fuel lines and oil pan, and a directional duct connected to the intake port of said manifold, a plurality of valves and controlling means for operating said valves, enabling said fluid spaces to be heated independently, consecutively, or simultaneously, and means for forcing the heated air from said unit to said duct and duct housings.
